UNITED STATES PATENT OFFICE.

NÁNDOR KOLÁR, OF BUDAPEST, HUNGARY, ASSIGNOR TO AUTOMETROGRAPH
RÉSZVÉNYTARSASÁG, OF BUDAPEST, HUNGARY, A CORPORATION OF HUNGARY.

BILL-DELIVERY APPARATUS.

1,251,386.

Specification of Letters Patent. Patented Dec. 25, 1917.

Application filed April 15, 1915. Serial No. 21,603.

To all whom it may concern:

Be it known that I, NÁNDOR KOLÁR, a subject of the King of Hungary, residing at Budapest, in the Kingdom of Hungary, have invented new and useful Improvements in Bill-Delivery Apparatus; and I do hereby declare the following to be a full, clear, and exact description of the same.

Printing mechanism of the kind in which 10 the account clamped in a frame is introduced into the casing containing the counting apparatus are well known in meters. In this known mechanism the casing contains a device by means of which the paper 15 sheet used for printing is capable of being pressed against the type with a relatively strong and uniform pressure.

As this pressure device is exceedingly sensitive as regards its precise adjustment and, 20 therefore, calls for frequent re-adjustment, it is the object of this invention to provide mechanism wherein the pressure device is located in the paper-carrying frame used for insertion so that it may be readily adjusted and held ready for use without the 25 necessity of opening the apparatus which in meters are usually kept under sealed closure.

According to this invention the printing mechanism comprises an expansible frame 30 adapted to clamp the paper sheet and an impression roller located between the paper sheet and the rear wall of the frame and adapted to press the paper against the type. This roller is so movably guided that in order 35 to move the paper sheet against the type the frame is spread apart in a certain direction during the impression throw of the roller.

The invention is illustrated by way of example in the accompanying drawings, in which:—

Figure 1 shows the printing counting apparatus, that is to say, the portion of the account printing mechanism arranged on 45 the meter, in a front view, the casing being shown in section.

Figs. 2 to 4 are transverse sections on the lines 2—2, 3—3, 4—4 respectively of Fig. 1 viewed in the direction of the arrows.

50 Fig. 5 is a front elevation of the printing frame, the paper-carrying frame being omitted therefrom.

Fig. 6 is a transverse section on the line 6—6 of Figs. 5 and 7.

Fig. 7 is a longitudinal section on the line 55 7—7 of Fig. 5, and

Figs. 8 to 10 are details.

The portion of the account-printing mechanism which is arranged on the meter comprises as shown in Fig. 1 a continuously indicating counting train A and a counting apparatus B indicating the amount in money corresponding to the consumption at the time being, this apparatus being set to zero in any well-known manner such as, for instance, by means of the heart-shaped cams 3 arranged on the shaft of the counting wheels 2. The two counting trains A, B are intermittently driven from the meter shaft by means of appropriate gearing. The 70 mechanism is inclosed in a casing 5 provided with an opening 6 for the insertion of the printing frame and adapted to be closed by a slide, flap or door 7. This door 7 is held closed by a bolt 9 which is rotatable about a pivot 8, Fig. 4.

The printing frame consists of a flat rectangular housing 10 open at the front, containing a frame 11 resiliently supported by springs 12 so that when the two parts 10 80 and 11 are assembled the breadth or thickness of the printing frame is relatively small, enabling its insertion in the casing of the apparatus to be effected in an easy manner. The frame 11 carries a second 85 frame 14 which is capable of being tripped up about a hinge 13 so that after being tripped the account sheet to be printed or several such sheets may be inserted between the two frames 11 and 14.

90 Secured to the rear wall of the housing 10 are two leaf springs 15 which support a frame consisting of two transverse bars 16 and lateral bars 17. The ends of the bars 17 are, as shown at 18, bent backward toward the rear wall of the housing 10. Guided on the bars 17 are the end pivots 19 of an impression roller 20 provided with an elastic coating and rotatably journaled in a bracket 21 attached to which is a connecting rod 22 provided with a handle 23.

95 Arranged on the housing 10 of the printing frame are, moreover, two spring actuated ratchet pawls 24 projecting through 100 openings 25 in the rear wall of the housing 10.

The operation is as follows:

Prior to use the impression roller 20 is

in the position shown in Figs. 5 and 7. The frame 14 is tripped up and the account sheet is inserted together with the indigo copy paper between the two frames 11 and 14 and 5 clamped therebetween. A key is then introduced through the key hole 26, shown in Fig. 4, the hole in the end of the key receiving in this action the end of a shaft 27 (Figs. 1 and 3).

10 As the key is rotated it first moves the bolt 9 laterally in the direction of the arrow 28 thereby freeing the door 7. The end of the key, moreover, enters the notch 29 in a disk 30 secured to the shaft 27 and 15 rotates this shaft until the latter is stopped by the engagement of a pawl 31 with a tooth 32 of a disk 33 which is likewise arranged on the shaft 27 (Fig. 3). As the door 7 is now released, the printing frame 10 can be 20 slipped through the opening 6 in the casing 5 in which action it is guided in recesses 34 (Fig. 3) of the frame portion 35. The printing frame is inserted so that the paper sheet or the frames 11 and 14 face the counting trains A and B. The counting wheels 25 of these trains are provided with raised type which form the printing type.

As soon as the printing frame is inserted to a sufficient depth into the casing 5, the 30 ratchet pawls 24 (shown in Fig. 7) engage the edge of the recess 34 (Fig. 3) and prevent the printing frame from being withdrawn. Now, by means of the handle 23 the impression roller 20 is pulled in the direction 35 of the arrow 36, that is to say, in the direction of the lines X—X, Y—Y (Fig. 1). In this action the trunnions 19 of the impression roller travel on to the straight part of the bars 17 which is nearer the frame 11 and 40 thereby exert pressure upon the springs 15 so that the roller 20 presses upon the paper sheet clamped between the frames 11 and 14 and forces it against the printing type of the counting apparatus. The trunnions 19 also 45 press against the projecting edge of the frame 11 and, therefore, press the portions 10 and 11 of the printing frame during the printing operation apart one from the other. While the impression roller 20 travels along 50 the bars 17 the printing operation takes place and when the roller reaches the end of its travel the trunnions 19 are again in contact with bent ends of the rollers 17, whereby the pressure on the paper sheet is relieved. 55 At the same time the bearing 21 presses against the lugs 37 of the ratchet pawls 24 by which action the printing frame is released. The printing frame can now be withdrawn from the casing 5 after which the 60 door 7 is closed by the action of springs 38. By the closing movement of the door 7 the pawl 31 is withdrawn from behind the tooth 32 of the disk 33 in any convenient manner, for instance, by a bell crank lever 40 which 65 is keyed to a shaft 39 (Figs. 1 and 3) there-

by enabling the shaft 27 to be further rotated by means of the key. A return rotation of the shaft 27 is counteracted by a ratchet wheel 41 co-operating with the ratchet pawl. While the shaft 27 completes 70 its rotation the tooth wheels 42 which are driven thereby will cause, by means of a cam groove 43 (Figs. 8 and 9) the shaft of the operating wheels 44 of the train B to be temporarily thrown out of engagement with 75 the counting wheels, thus enabling the latter to be reset to zero by means of the arrangement shown in Fig. 10 which in itself is well known, before the key can be withdrawn from the key hole 26 prior to the 80 completion of the rotation of the shaft 27.

The details of the construction and the manner of accommodating the printing device in the frame may vary at will but it is important that the printing device is not located within the casing which is arranged on the meter but in the withdrawable printing frame, thereby doing away with the necessity of providing each meter with its individual printing mechanism. 85

By using several carbons or copying sheets, several impressions may obviously be obtained simultaneously.

The mechanism may, moreover, be further modified by the impression roller being 90 capable of being withdrawn from the printing frame so that the printing frame and the paper sheet are inserted in the apparatus first and the impression roller is introduced subsequently. 95

In the place of an impression roller the printing frame may contain an equivalent impression means, such as a straight or curved platen.

What I claim and desire to secure by Letters Patent is:

1. In a meter the combination of counting apparatus having counting trains provided with printing wheels, a mechanism for printing a record comprising a movable impression roller arranged in a frame constructed in the form of an expandible housing containing the record sheet and adapted to be inserted through a slot in the meter casing with the recording sheet facing the 110 type wheels of the counting train so as to be pressed against the printing wheels by the expansion of the frame in the operation of the impression roller, substantially as set forth. 115

2. In a meter, the combination of counting apparatus having counting trains provided with printing wheels, a mechanism for printing a record comprising an expandible housing with two clamping members for 125 holding the record sheet on one side, an elastic frame spring supported at the opposite side of the housing and an impression roller movable along the said elastic frame whereby in the movement of the impression 130

roller between the said frame and the record sheet clamping parts, the said housing is expanded to force the record sheet into contact with the printing wheels of the counting apparatus, substantially as set forth.

3. In a meter the combination of counting apparatus having counting trains provided with printing wheels, a mechanism for printing a record comprising an expandible housing adapted to be inserted through a slot in the meter casing, two clamping members on one side of the housing for clamping a record sheet, a spring supported frame on the opposite side of the housing having

guide rails with inclined parts at top and bottom, a movable impression roller adapted to travel along the said guide rails and between the same and the said clamping parts and a bearing bracket for journaling the trunnions of the impression roller and provided with a pull rod for the actuation of the said roller, substantially as set forth.

In testimony whereof I have affixed my signature in presence of two witnesses.
